UNITED STATES PATENT OFFICE.

ABRAHAM L. ELIASOFF, OF BROOKLYN, AND CHARLES BIRNBAUM, OF NEW YORK, N. Y.

DESIGN FOR A GEM-SETTING.

57,217.

Specification for Design.

Patented Mar. 8, 1921.

Application filed August 14, 1920. Serial No. 403,615. Term of patent 14 years.

To all whom it may concern:

Be it known that we, ABRAHAM L. ELIASOFF and CHARLES BIRNBAUM, citizens of the United States of America, residing in the borough of Brooklyn, county of Kings, city and State of New York, and in the borough of Bronx, county of Bronx, city and State of New York, respectively, have invented a new, original, and ornamental Design for a Gem-Setting, of which the following is a specification, reference being

had to the accompanying drawing, forming a part thereof.

Figure 1 shows a perspective view of the setting with the gems therein appearing in dotted lines.

Fig. 2 is a side elevation of the setting.

We claim:

The ornamental design for a gem setting, substantially as shown.

ABRAHAM L. ELIASOFF.
CHARLES BIRNBAUM.
